UNITED STATES PATENT OFFICE

LOUIS STEIN, OF CHICAGO, ILLINOIS

LOOSE LEAF BINDER

Application filed September 24, 1930. Serial No. 483,988.

The invention pertains to loose leaf binders of the type in which a stack of sheets is retained in position between the covers of the binder by means of a plurality of posts extending between two pivotal wings which are secured within the back of the binder, the posts being anchored at one end to one of the wings and detachably secured or locked to the other of the wings.

10 One object of the invention is to provide a loose leaf binder of the character above indicated having a construction such that it is capable of being manufactured at a substantially lower cost than has been possible of binders of this type as previously constructed.

15 Another object is to provide a loose leaf binder of the post type, in which the anchoring and locking wings are of such character that they may be made of very small thickness and thus avoid undesirable bulkiness at the rear edge of the binder.

20 A further object is the provision of an improved construction for the locking wing such as to reduce the number and cost of the parts, and at the same time permit an easy and effectual locking operation.

25 Another object is to provide a binder having an improved post-anchoring wing of extremely simple character and low in manu-

30 facturing cost.

The objects of the invention thus set forth, together with other and similar advantages, are attained by the construction and arrangement illustrated in the accompanying drawings, of which:

35 Figure 1 is a fragmentary perspective view of a binder embodying my invention with the parts in assembled relation but omitting the stack of sheets for the sake of clearness.

40 Fig. 2 is a similar view with the parts in position to receive a stack of sheets.

Fig. 3 is an enlarged fragmentary sectional view through the rear portion of the binder at one of the retaining posts.

45 Fig. 4 is a fragmentary sectional view illustrating the method of fastening the locking slide to the flexible wing member.

50 Fig. 5 is a sectional view of the anchoring wing taken through one of the posts before the parts have been secured together.

Fig. 6 is a fragmentary plan view showing one of the anchoring posts secured in position.

55 My invention as illustrated is applied to a binder having covers 7 and 8 connected by a back 9. A plurality of sheet-retaining posts 10 are anchored upon a lower pivotal wing generally designated by the numeral 11, which posts are adapted to receive a stack of perforated sheets 12. At their upper or free 60 ends, the posts 10 are adapted to be detachably secured to an upper or locking wing generally designated by the numeral 13.

65 In the preferred embodiment of my invention the lower or anchoring wing 11 is simply constructed to reduce to a minimum the number of parts necessary to be employed, and also to reduce the thickness of the wing structure. To this end it comprises a hinge member 14 which may be composed of 70 the same material as that of the covers 7 and 8. The material employed is usually of a flexible character, being of cloth or fabric in the case of binders of good quality, or of paper or fiber in the case of cheaper binders. 75 Said hinge member 14, as shown, is in the form of an elongated strip of flexible material hinged at the lower side edge of the back 9.

80 Upon the inner face of this flexible hinge member 14 is secured a plate 15 preferably in the form of an elongated metallic strip, the central portion of which is shown as being fastened to the flexible wing member 14 as by means of one or more rivets 16. The 85 metallic plate or strip 15 constitutes a reinforcing member for the anchoring wing and is also utilized in fastening the lower ends of the posts 10 to the wing.

90 The retaining posts are constructed in two sections comprising a tubular base section 17 internally threaded to receive an upper portion or extension 17a. For the purpose of fastening the posts to the anchoring wing, the tubular base section of each post is provided 95 with a thin and relatively flat head or abutment 18 between which and the strip 15 is clamped the flexible hinge or wing member 14.

100 To reduce to a minimum the bulkiness of

the wing structure, the base section 17 of each post is secured to the strip or plate 15 by a shrinking or contraction of the metal about the post. Thus as shown in Fig. 5 the tubular base section of each post is inserted through an aperture in the flexible wing member 14 and in the metallic strip 15, the latter aperture being formed in a raised annular portion or boss 19 and being made of a diameter such as to receive snugly the tubular base section 17 of the post. The contraction of the metal about the post is effected by depressing the annular boss 19 flat upon the flexible strip 14, a suitable tool (not shown) being used for this purpose; and preferably a series of indentations 20 are formed in the metal adjacent the post so as to increase the effectiveness of the gripping action about the post through a further compression of the metal.

The upper or locking wing is also made relatively thin and flat, and may be manufactured very cheaply. Thus it is composed essentially of only two parts including an inner flexible hinge member 21 hinged at the upper edge of the back, and an outer locking slide 22. The latter in the preferred embodiment is in the form of a channel member constructed from a flat sheet of metal bent midway between its side edges into channel form so as to form opposed walls 23 and 24. This channel member may be made of any suitable material possessing the desired rigidity such, for example, as sheet metal, and it is mounted for sliding movement upon the inner hinge member 21 by any suitable or preferred means such as tubular rivets 25 operating in slots 25^a in the opposed walls 23 and 24 of the slide.

To effect an interlocking action between the slide and the upper ends of the post extensions 17^a, the inner wall 24 of the slide is provided in the present instance with keyhole slots 26 adapted to receive grooved heads 27 on the upper ends of the post extensions 17^a. The hinge member 21 within the slide has openings 27^a therein forming sockets to receive the heads 27 and acting to prevent transverse movement of the heads relative to the hinge member, so that it will be apparent that the interlocking action may be effected by positioning the slide so that the enlarged ends of the keyhole slots 26 thereof receive the heads 27, and thereupon moving the slide until said heads interengage with the narrow portions of the slots. In the wall 23 of the slide, opposite the large ends of the slots 26, small openings 28 are formed to permit the operator to see the heads 27 of the posts as the slide is slipped onto the posts, thus facilitating the positioning of the slide.

It has been found that with the construction thus provided the locking slide may be operated by the exertion of very small force endwise of the wing, and for this purpose of

facilitating movement of the slide it may be equipped with a ring 29 at one end (Fig. 2), or the wall portion 23 thereof may be formed with knurled bosses 30 (Fig. 1) through the medium of which the slide may be moved. 70

An advantage of substantial importance in the construction provided is the reduction in the number of parts to a minimum, coupled with the simple character of their construction such that they may be manufactured at a very low cost as compared to prior structures. Also the wing structure is such in each instance that the thickness thereof is small and hence the rear edge of the binder is relatively thin and flat, avoiding undue bulkiness. 75

I claim as my invention:

1. A loose leaf binder comprising a back, a plurality of posts for retaining a stack of perforated sheets to be bound, an anchoring wing hinged at one edge of said back and carrying said posts, and a locking wing comprising a flexible hinge member and a relatively rigid locking member channel-shaped in cross-section to receive said hinge member, said locking member being slidably mounted on the hinge member for movement into and out of interlocking relation with said posts. 85

2. A loose leaf binder comprising a back, a plurality of headed posts for retaining a stack of perforated sheets to be bound, an anchoring wing hinged at one edge of said back and carrying said posts, and a locking wing comprising a flexible hinge member and a relatively rigid locking member channel-shaped in cross-section to receive said hinge member, said locking member being slidably mounted on said hinge member and having a plurality of apertures in one wall thereof adapted to receive said posts, and said apertures being keyhole shaped to effect an interlocking engagement with said posts as an incident to a longitudinal movement imparted to the locking member. 95

3. A loose leaf binder comprising a back, a headed post for retaining a stack of perforated sheets to be bound, an anchoring wing hinged at one edge of said back and carrying said post, and a locking wing comprising a flexible hinge member and a relatively rigid locking member providing two opposed walls between which said flexible hinge member is retained, the inner one of said walls and said hinge member being apertured to receive the free end of said post, and said aperture in the locking member being keyhole shaped to provide an interlocking engagement between the post and the locking member as an incident to the movement of the locking member relative to the hinge member. 110

4. A loose leaf binder comprising a back, a headed post for retaining a stack of perforated sheets to be bound, an anchoring wing hinged at one edge of said back and carrying said post, and a locking wing comprising a 115

flexible hinge member and a relatively rigid locking member providing two opposed walls between which said flexible hinge member is retained, the inner one of said walls and said hinge member being apertured to receive the free end of said post, and the aperture in said hinge member forming a socket acting to prevent transverse movement of the post, said aperture in the locking member being key-hole shaped to provide an interlocking engagement between the post and the locking member as an incident to the movement of the locking member relative to the hinge member.

5 hinge member, said locking member being slidably mounted on said hinge member and having a plurality of keyhole shaped apertures in one wall thereof adapted to receive said posts and to effect an interlocking engagement with said posts as an incident to a longitudinal movement imparted to the locking member, said locking member having in its other wall apertures aligned with the enlarged portions of said keyhole-shaped apertures and smaller than the ends of said posts.

15 In testimony whereof, I have hereunto

20 75

affixed my signature.

LOUIS STEIN.

80

5. A loose leaf binder having a channel-shaped locking slide adapted for interlocking engagement with a headed sheet-retaining post, and a flexible hinging member entered into the channel of said slide and having the 20 slide mounted thereon for longitudinal movement.

85

6. A wing construction for loose leaf binders comprising an elongated member adapted to be mounted on the binder back 25 for pivotal movement along one of its edges, and a channel-shaped substantially rigid slide embracing said member and mounted thereon for limited sliding movement, said slide having a keyhole slot formed in one side 30 thereof with its narrow portion extending parallel to the path of movement of the slide.

90

7. A wing construction for loose leaf binders comprising an elongated member adapted to be mounted on the binder back for 35 pivotal movement along one of its edges, a channel-shaped substantially rigid slide embracing said member and secured for limited sliding movement thereon, one side of said slide having means thereon operable in the 40 sliding movement to fix the slide to a post, and means on the other side of the slide providing a roughened surface adapted to be engaged by an operator to move the slide.

95

8. A loose leaf binder having a back, a pair 45 of covers, a thin flexible member mounted on the back adjacent the connection with one of said covers, a pair of sheet-retaining posts passing through said member and having flat heads adapted to engage with the outer face 50 of the member, and a thin elongated metallic reinforcing plate on the inner face of said member apertured to receive said posts, said plate having annular anchoring portions encircling the respective posts bent from a 55 frusto-conical form into the plane of the plate so as to be compressed into tightly gripping relation to the posts.

100

9. A loose leaf binder comprising a back, a plurality of headed posts for retaining a 60 stack of perforated sheets to be bound, an anchoring wing hinged at one edge of said back and carrying said posts, and a locking wing comprising a flexible hinge member and a relatively rigid locking member channel-shaped in cross-section to receive said
